UNITED STATES PATENT OFFICE.

FRANK SHARP, OF SOCORRO, TERRITORY OF NEW MEXICO.

CAN-OPENER.

SPECIFICATION forming part of Letters Patent No. 253,432, dated February 7, 1882.

Application filed July 5, 1881. (Model.)

To all whom it may concern:

Be it known that I, FRANK SHARP, of Socorro, in the county of Socorro and Territory of New Mexico, have invented a new and useful Improvement in Can-Openers, of which the following is a full, clear, and exact description.

In the accompanying drawings, Figure 1 is a sectional side elevation of my improvement. Fig. 2 is a sectional end elevation of the same, taken through the line $x-x$, Fig. 1. Fig. 3 is a plan view of the same.

Similar letters of reference indicate corresponding parts.

The object of this invention is to facilitate the opening of cans and promote convenience in adjusting the opener.

The invention consists in a can-opener constructed with a handle, a bar attached to the handle and having a curved point and a perforated lug upon its forward end, the swiveled screw having a thumb-wheel upon its inner end, and the cutter having a shank made with a screw-hole to receive the swiveled screw and a perforation to receive the supporting-bar, whereby the cutter can be adjusted by the hand that grasps the handle, as will be hereinafter fully described.

A is the handle of the can opener, to the forward end of which is securely attached a bar, B. Upon the forward end of the bar B is formed a curved point, C, to be forced through the top of the can and to serve as a pivot to the opener when in use. Upon the upper side of the forward end of the bar B is formed a lug, D, to which is pivoted the forward end of a screw, E. The rear end of the screw E is pivoted to the forward end of the handle A, and has a thumb-wheel, F, attached to it, so that the said screw E can be conveniently turned by the hand that grasps the handle A. The screw E passes through a screw-hole in the shank G of the cutter H. The shank G of the cutter H

has a perforation formed through it to receive and fit upon the bar B, so that the cutter can be moved toward or from the point C by turning the screw E in one or the other direction. The cutter H is made in the shape of an arrow-head, as shown in Fig. 2, and its sides are rounded off, so that when being used the said cutter will turn down the edges of the can-top along the opposite sides of the cut, leaving the upper side of the said can-top perfectly smooth.

In using the can-opener the point C is thrust through the center of the top of the can and the cutter is adjusted to make the cut at the desired distance from the edge of the said can-top by turning the screw E in one or the other direction. The cutter is then forced through the top of the can and is carried around the point C as a center for any desired distance. In using the cutter to open square or oblong boxes or cans the point C is thrust through the top of the can near the center of one edge. The knife H is then adjusted in proper position and a semicircular cut is made in the top of the can in the manner hereinbefore described.

Having thus fully described my invention, what I claim as new, and desire to secure by Letters Patent, is—

A can-opener constructed substantially as herein shown and described, consisting of the handle A, the bar B, having a curved point, C, and a perforated lug, D, upon its forward end, the swiveled screw E, having thumb-wheel F upon its inner end, and the cutter H, having in its shank G a screw-hole to receive the screw E and a perforation to receive the bar B, as set forth.

FRANK SHARP.
